UNITED STATES PATENT OFFICE

JOHANNES PLUM, OF NEW YORK, N. Y., ASSIGNOR TO FANTAIL BOAT CORPORATION, OF NEW YORK, N. Y.

SPEED BOAT

Application filed October 17, 1928. Serial No. 312,956.

This invention relates to boats of the hydroplane type, in which speed and weight carrying ability are of paramount importance, and is in the nature of an improvement on 5 the device shown, described and claimed in my patent on speed boats, No. 1,618,995, issued March 1, 1927.

These improvements include the provision of a more rigid and stronger forward planing surface, which will afford a greater resistance to strains; the provision of means for elevating and lowering the fan shaped hydroplane element at the stern of the boat to trim the boat to the most favorable planing angle 10 in accordance with the weight or load carried by the boat; means for efficiently retaining the said fan shaped hydroplane element in its adjusted position; and the provision of yielding connections between the hydroplane and 15 boat stern, which, while positive, will permit moderate relative movement in approximately horizontal planes.

The improvement in the forward planing surface consists of a modification in the bottom 20 of the hull of the boat above which the motor is located. It has been found that at high speed or in rough water the "pounding" effect from the impact of the bottom of the hull with the water causes a loosening and 25 separation of the said bottom and upwardly extending sides of the hull at the point where they meet. To overcome this the present hull is formed with the outer portion thereof of the usual contour which is designed for the 30 best results in speed boats, and an inner shell 35 in the shape of an inverted arch between which and the outer portion there may be a filling of any light but firm material, such as balsa wood.

These important features are attained by the novel design, construction and arrangement of parts hereinafter described and illustrated in the accompanying drawing, forming a material part hereof, and in 40 which:—

Figure 1 is a side elevational view of an embodiment of the invention as disposed with relation to the surface of water.

Figure 2 is a top plan view of the same.

Figure 3 is an enlarged transverse sectional view taken on line 3—3 of Figure 1.

Figure 4 is a similar view taken on line 4—4 of Figure 1.

Figure 5 is a further enlarged fragmentary 55 side view of the stern, parts being broken away and other parts in section to show the construction.

Figure 6 is a fragmentary side elevational view of the hydroplane supporting piston, 60 partially in section.

Figure 7 is a partial side, partial sectional view of the piston rod as attached to the hydroplane.

Figure 8 is a front elevational view of the 65 same, partially in section.

The boat as shown herewith, is generally designated by the numeral 10, and is provided with a cockpit 11, in its central portion for the occupants.

Extending centrally from the bow to a point somewhat in excess of half the length of the boat, is a keel 12, having at each side angular planing surfaces 13, forming an underbody having straight upturned lateral 75 edges merged into the sides of the boat 10. Extending from side to side of the hull of the boat and spaced a short distance above the outside bottom of the hull a second wall in the shape of an inverted arch is located, the space therebetween being filled with any preferred light but firm material 14, such as balsa wood or the like. The ends of this inner wall being curved where they meet the side walls 10 of the hull, serve to brace and 80 strengthen all this section of the boat.

In actual practice it has been demonstrated that the pounding on the bottom of the hull caused by the impact of the boat with the unyielding surface of the water, would result in the breaking away and forcing upwardly and inside the boat of the outer ends of the hull bottom 13. This new type of construction has obviated this difficulty and prevented the said breaking away and separation of the bottom and side portions of the hull.

The rearward portion of the boat is preferably arcuate in cross section with raised side walls as shown, and it is to be noted that 100

a distinct line of demarcation 15 is formed, through the shouldered portion of which extends a propeller shaft 16.

The rear end of the propeller shaft has 5 an outboard bearing in a rudder 17, adjacent to which is a propeller 18, the shaft being driven by a motor, not shown, carried in the boat as is customary.

It is to be noted that the shaft 16 extends 10 downwardly at a considerable angle so that the propeller is completely submerged well under the rear portion of the boat.

Below the stern a recess 19 is formed in the boat bottom, at the outer end of which 15 is a roller 20 mounted at the end of a plunger 21 pressed downwardly normally by a resilient member 22.

A pair of brackets 23 are rigidly mounted on the flooring 24 of the boat above the recess 19, and fixed between these brackets is a cylinder 25 at an angle of substantially ten degrees with the normal plane of the boat. If this cylinder 25 should be set in a vertical plane the fantail hydroplane would rotate in 25 a precisely horizontal plane, but with the angular pitch of the cylinder shown herein, the swing of the fantail is limited, and if the boat rolls or careens the fantail will balance itself.

20 A head 26, provided with a central inlet 27 is bolted to the upper end of the cylinder and a port 28 is arranged near its contracted lower end, in which end is a packing held by the gland 29.

25 Passing into the cylinder 25, through the packing, is a piston rod 30 having at its inner end a piston 31, secured by a nut, this piston having a central, full diameter narrow portion 32 on both sides of which are angular, annular grooves 33, tapering outwardly to distinct shoulders 34 at the ends of the threaded portions in which are engaged rings 35, to impinge upon packings 36, such as leather, these packings having inreaching cylindrical flaps 36' adapted to be pressed outwardly 40 against the wall of the cylinder by any liquid 45 which may enter the grooves 33, as best seen in Figure 6.

The outer end of the piston rod 30 is provided with a flange 37 having a plurality of angular braces to stiffen the structure.

The flange 37 has upon its opposite upper sides, round bottomed transverse grooves 38, and a flat bottom to seat upon a resilient level cushion 39, such as rubber, interposed between it and the levelled upper surface of the fantail hydroplane 40, the same having a recess 41 to receive the cushion element 39.

The hydroplane is essentially fan shaped 50 in outline and capable of pivoting on the axis of the piston rod 30, and also rising to the limit of the roller 20.

The hydroplane is secured to the flange 37 by clamps 42, set in transverse recesses 43, in 55 its under side, these clamps having paired rods

44 formed integrally near its ends, these rods extending through openings in the cushion 39 and flange 37 to pass through corresponding openings in the ends of clamp bars 45 seated in the grooves 38, these bars being shaped to 70 clear at their ends and are provided with nuts 46.

The bars 45 are sufficiently narrow and provided with rounded lower edges to seat in the recesses 38, which have at their outer 75 edges raised ledges 38', as best seen in Figures 7 and 8.

At a suitable point in the body of the boat is a tank 47, containing compressed air from any convenient source, and leading from the tank are connections to valves 48-49, controlling pipes 50-51, leading respectively to the cylinder parts 28-27, between which the piston 31 operates.

A liquid packing, such as oil, glycerine, etc., is entered into the cylinder above the piston 31 and packing element 29, as at 52-53 in Figure 5.

The valves 48-49 are of the three way type and arranged to be controlled by handles 48-48^b and 49^a-49^b, by which air may be admitted under a very considerable pressure into the cylinder, in a manner to raise and lower the piston, and consequently the fantail hydroplane, maintaining it at the height 95 found to be calculated to obtain the best planning angle for the boat with relation to the weight and load carried thereby.

Obviously, as air is admitted to one side of the piston, the air on the other side must be 100 allowed to escape, which is accomplished by the type of valves used.

The foregoing disclosure is to be regarded as descriptive and illustrative only, and not as restrictive or limitative of the invention, 105 of which obviously an embodiment may be constructed including many modifications without departing from the general scope herein indicated and denoted in the appended claims.

Having thus described the invention, what is claimed as new and desired to secure by Letters Patent is:—

1. A boat having a hull of arcuate cross section throughout its length, a keel, a bottom composed of flat plates angularly disposed and converging at the keel, side plates joining said bottom and merging into the sides of said hull, said bottom having a shouldered step reaching to the hull at a point midway the length of the boat, and a filler between said bottom and hull.

2. A boat having a hull of arcuate cross section throughout its length, a keel, a bottom composed of flat plates angularly disposed and converging at the keel, side plates joining said bottom and merging into the sides of said hull, a stepped shoulder at the end of said bottom extending to the hull, and a 130

firm light weight substance interposed between the bottom and hull.

3. A boat having a hull of arcuate cross section throughout its length, a keel, a bottom composed of flat plates angularly disposed and converging at the keel, side plates joining said bottom and merging into the sides of said hull, a stepped shoulder at the end of said bottom extending to the hull, a firm light weight substance interposed between the bottom and hull, a recess in the underside of said hull adjacent the stern of the boat, and a hydroplane pivoted to rotate freely below and rearward of the stern recess.

10 4. A boat having a recess in its bottom at the stern, a rotatable hydroplane having a fan-like contour, said hydroplane being partially disposed in the stern recess, a pivotally mounted stem for said hydroplane, said stem being at an angle to the horizontal plane of the boat, and means for raising and lowering the hydroplane.

15 5. A speed boat hydroplane adjusting means comprising a bracket fixed on the floor of the boat, a cylinder fixed in the bracket and inclined at approximately an angle of ten degrees to the vertical, a piston movable in said cylinder, means to adjust the height of said piston, a rotatable hydroplane, and a piston rod having a flanged end fixed to said hydroplane.

20 6. A speed boat hydroplane adjusting means comprising a forwardly inclined bracket on the boat floor adjacent the stern, a hydroplane having a recess with a leveled bottom in its upper surface, a flange secured in the recess, a cushion element interposed, a piston having a rod fixed to said flange, an inclined cylinder carried by said bracket to receive said piston, ports in said cylinder above and below said piston, and controllable means for admitting a gaseous body through said ports.

25 7. A speed boat hydroplane adjusting means comprising a forwardly inclined cylinder at the stern of the boat, a piston operable therein, said piston having packings adapted to prevent the passage of air, a rod in said piston, a rotatable hydroplane fixed at the lower end of said rod, liquid packings in said cylinder at the rod and above the piston, a source of compressed air, and valves to control the admission and exhaust of the air to either side of said piston.

30 8. A speed boat hydroplane adjusting means comprising a forwardly inclined cylinder at the stern of the boat, a piston operable therein, said piston having packings adapted to prevent the passage of air, a rod in said piston, a hydroplane yieldingly mounted on said rod to raise, lower and pivot therewith, a source of compressed air connected with said cylinder above and below the piston, manual means for controlling the ingress and egress of air thereto, and means

to prevent the loss of air from said cylinder.

35 9. A speed boat hydroplane adjusting means comprising a forwardly inclined cylinder at the stern of the boat, a piston operable therein, a fan-shaped rotatable hydroplane yieldingly mounted on the lower end of the piston rod, means for adjusting the piston in said cylinder, and a resiliently mounted roller to impinge on the upper surface of said hydroplane, said piston and hydroplane being capable of movement in the plane of the axis of said cylinder.

40 In testimony whereof I have hereunto affixed my signature.
